UNITED STATES PATENT OFFICE.

EUGENE IRVING HANSON, OF NEW ROCHELLE, NEW YORK, ASSIGNOR TO H. R. MALLINSON & CO., OF NEW YORK, N. Y., A FIRM COMPOSED OF HIRAM ROYAL MALLINSON AND E. IRVING HANSON.

DESIGN FOR A TEXTILE FABRIC.

50,304.

Specification for Design.

Patented Feb. 13, 1917.

Application filed September 23, 1916. Serial No. 121,886. Term of patent 3½ years.

To all whom it may concern:

Be it known that I, EUGENE IRVING HANSON, a citizen of the United States of America, and a resident of New Rochelle, in the county of Westchester, State of New York, have invented a new, original, and ornamental Design for a Textile Fabric, of which the following is a specification, reference being had to the accompanying drawing, showing my design.

The drawing shows a face view of a portion of fabric bearing my design.

In the drawing *a*, *b*, *c*, *d* and *e* designate differently colored stripes, all said stripes being produced upon a substantially circu-

lar field defined by an irregular wavy line and all said stripes being separated or defined not by straight lines, but by irregular wavy lines whereby the monotonous continuity of the stripes is broken and a soft draped effect is imparted to the fabric bearing my design, the whole being produced upon the white background *f*.

The design is intended to be repeated on the fabric.

I claim:—

The design for a textile fabric as shown and described.

E. IRVING HANSON.
